UNITED STATES PATENT OFFICE.

HENRY W. HIRSCHFELD, OF WEST MERIDEN, ASSIGNOR TO ROGERS & BROTHER, OF WATERBURY, CONNECTICUT.

DESIGN FOR SPOONS AND FORKS.

Specification forming part of Design No. 11,171, dated April 22, 1879; application filed February 17, 1879.
[Term of patent 7 years.]

To all whom it may concern:

Be it known that I, HENRY W. HIRSCHFELD, of West Meriden, in the county of New Haven and State of Connecticut, have invented a new Design for Spoons and Forks; and I do hereby declare the following, when taken in connection with the accompanying drawing and the letters of reference marked thereon, to be a full, clear, and exact description of the same, and which said drawing constitutes part of this specification, and represents a face view.

This invention relates to a design for the handle of spoons, forks, and like articles of table-service; and consists in the configuration and ornamentation herein described, and shown in the accompanying illustration.

About midway of the length of the handle is a boss, *a*, from which the handle gradually expands toward the end, with a bead on each

side, turning inward at the end in semicircular form, meeting at the center, and surmounted by a Gothic-shaped tip, *b*, as shown. Diagonally across the face of the handle is an ornamented band, *c*, which is the chief characteristic of the ornamental part of the design.

I claim—

The design for spoon and fork handle, consisting of a boss, *a*, from which the handle expands toward the end, with a bead on each edge meeting at the end in substantially two semicircles, surmounted by a Gothic-shaped tip, *b*, and with a diagonal band across the face, as described, and shown in the accompanying illustrations.

HENRY W. HIRSCHFELD.
